US00D981230S

(12) **United States Design Patent** (10) Patent No.: **US D981,230 S**
(45) Date of Patent: **** Mar. 21, 2023**

(54) **LID FOR PACKAGING**

(71) Applicant: **TETRA LAVAL HOLDINGS & FINANCE S.A.**, Pully (CH)

(72) Inventors: **Maurizio Filippini**, Modena (IT); **Daniele Palladino**, Scandiano (IT); **Angelo Sorbara**, Rubiera (IT); **Francesca Tavoni**, Modena (IT)

(73) Assignee: **TETRA LAVAL HOLDINGS & FINANCE S.A.**, Pully (CH)

(**) Term: **15 Years**

(21) Appl. No.: **35/511,940**

(22) Filed: **Nov. 27, 2020**

(80) **Hague Agreement Data**

Int. Filing Date: **Nov. 27, 2020**

Int. Reg. No.: **DM/211515**

Int. Reg. Date: **Nov. 27, 2020**

Int. Reg. Pub. Date: **May 28, 2021**

(57) **CLAIM**

The ornamental design for lids for packaging, as shown and described.

DESCRIPTION

1. Lid for packaging

2. Lid for packaging

3. Lid for packaging

4. Lid for packaging

1.1 : Perspective

1.2 : Right

1.3 : Left

1.4 : Back

1.5 : Front

1.6 : Top

1.7 : Bottom

2.1 : Perspective

2.2 : Right

2.3 : Left

2.4 : Back

2.5 : Front

2.6 : Top

2.7 : Bottom

3.1 : Perspective

3.2 : Right

3.3 : Left

3.4 : Back

3.5 : Front

3.6 : Top

3.7 : Bottom

4.1 : Perspective

4.2 : Right

4.3 : Left

4.4 : Back

4.5 : Front

4.6 : Top

4.7 : Bottom

The broken line shown is for the purpose of illustrating portions of lids for packaging and forms no part of the claimed design.
